Des. 210,543

Patented Mar. 19, 1968

210,543

BALL PROJECTOR OR THE LIKE

Torao Nakayama, 38, 2-chome Hatsune-cho,
Naka-ku, Yokohama, Japan

Filed Mar. 16, 1966, Ser. No. 1,495

Term of patent 14 years

(Cl. D34—5)

FIG. 1

FIG. 2

FIG. 3

FIG. 4

FIG. 5

FIG. 6

FIG. 7

FIG. 1 is a perspective view of the ball projector or the like, showing the new design;

FIG. 2 is a front elevation view thereof;

FIG. 3 is a side elevation view thereof with the handle portion in the released position;

FIG. 4 is a top plan view thereof;

FIG. 5 is a bottom plan view thereof;

FIG. 6 is a sectional view taken on line 6—6 of FIG. 2; and

FIG. 7 is a sectional view taken on line 7—7 of FIG. 3.

I claim:

The ornamental design for a ball projector or the like, substantially as shown.
